ABSTRACT OF THE DISCLOSURE

There is provided a process for electrolyzing a dissolved substance to give a dissolved product wherein the susceptibility of the process to diffusion limitation is decreased by subjecting at least one electrode to a wiping action while immersed in the electrolyte whereby the stagnant boundary layer adjacent the electrode is at least partially removed.

This invention relates to electrolytic processes which are subject to diffusion limitation at the surface of solid electrodes.

According to the invention there is provided an electrolytic process of reduced susceptibility to diffusion limitation wherein at least one electrode is subject to a wiping action whilst immersed in the electrolyte.

According to the invention there is also provided an apparatus which may be used as an electrolytic cell having a reduced susceptibility to diffusion limitation which contains one or more anodes and cathodes at least one of which is equipped with means for subjecting it to a wiping action.

An electrolytic process is said to be subject to diffusion limitation when there is for example an inadequate rate of diffusion of a product of the electrolysis away from an electrode surface or of a reactant from the electrolyte to that electrode surface or both. The result can be a decrease in the current efficiency at that electrode surface, or a decrease in yield or both. These can be compensated by a decrease in current density, but at the cost of decreased output.

It is preferable that the wiping of the electrode should be over substantially the whole of the electrolytically active surface of the electrode. It is preferable that the pressure exerted by the wiper on the electrode surface shall be sufficient to remove substantially all the stagnant boundary layer.

In a preferred form of the invention the wiper is of a deformable material which wipes the surface of the solid electrode without causing appreciable abrasion, for example soft rubber material, brushes or plastic mesh fabric.

It is a matter of convenience whether the solid electrode is fixed and its surface wiped by the moving blade or vice versa. The relative movement is conveniently rotational but may be for example linear. The relative speed required between the electrode and the wiper depends on the current density and increases quite rapidly with increased current density. With practical current densities and wiping efficiency it appears to be sufficient to wipe the surface at intervals of 0.1–3 seconds.

The invention is useful for example in processes where the reaction species is not electrostatically attracted to the electrodes e.g.:

(a) Where the reacting species is non ionic e.g. electrolytic reduction of nitro benzene to azobenzene or electrolytic reductive dimerisation of acrylonitrile to adiponitrile and hexamethylene diamine; or

2

(b) Where the charge of the reacting species is the same as that of the electrode at whose surface it reacts, e.g. electrolysis of nitrite to produce hyponitrite, of nitrate to produce hydroxylamine or of bisulphite to produce dithionite. Other cases are:

(c) Where the ion has a low diffusion co-efficient, for example in Kolbe's electrolysis of the alkali salts of carboxylic acids to form hydrocarbons etc.; and

(d) In general where reaction conditions demand a high current density.

The requirements for cathode materials in electrolytic process are first that they are not seriously attacked by the catholyte during the process and second that at a high current density the required reaction is the major electrode process. The second requirement can be met by the use of metals with high hydrogen overpotentials.

Overpotential may be defined as the difference, under given conditions, between the potential at which a reaction is observed to proceed and the thermodynamically reversible value. Therefore at the surfaces of metals with high hydrogen overpotentials e.g. mercury, lead, tin, bismuth, zinc, thorium etc. cathode reactions other than hydrogen liberation take place at cathode potentials higher than those thermodynamically required for hydrogen liberation. However we have also found that some metals which, according to published data, have low hydrogen overpotentials and would therefore be expected to liberate hydrogen at all but the lowest cathode potentials, for example transition metals, when used as the cathode in the process of the invention, do in fact give good yields of products formed at the cathode at high current densities and cathode potentials.

The mechanism by which such metals are usable is not certain but it appears to be due to either or both of (a) removal of the diffusion limited boundary layer by the wiping action thus removing the reaction product and allowing the reactant species access to the cathode surface and (b) poisoning of the cathode surface giving it an effective hydrogen overpotential greater than the published value.

Thus for example, in the process for the production of dithionite by the electrolytic reduction of bisulphite, titanium, chromium and nickel are suitable cathode materials even if the current density is high. Stainless steels from the American Iron and Steel Institute (AISI) 300 and 400 series are also suitable. It is believed that some poisoning of the cathode surface by sulphur takes place.

Also for example in the process for the production of hydroxylamine by the electrolytic reduction of nitrate, titanium is a suitable cathode material. The presence of a poison for example mercuric ions in the cathode compartment is advantageous in this process.

The embodiment of the invention using a wiped cathode is particularly useful for the production of dithionites by the electrolytic reduction of bisulphite with process conditions in general the same as when using a mercury cathode as described in our co-pending British application No. 27,203/62. It can be used for the production of dithionites of potassium, sodium, ammonium and zinc and particularly of sodium.

In the process for the production of sodium dithionite the catholyte may conveniently contain a small amount for example up to 20% of a water miscible alcohol, for example methyl or ethyl. The catholyte may also contain a small amount for example 0.02% to 5% of an organic base, for example aliphatic or aromatic, primary, secondary or tertiary amines, heterocyclic nitrogen bases e.g. pyridine, and ammonia/aldehyde or ketone condensation compounds.

The drawings show two electrolytic cells embodying the principles of the invention. The cell shown in FIGURES 1 and 2 has a stationary cathode and a rotating wiper and

the cell shown in FIGURES 3, 4 and 5 has a rotating cathode and stationary wipers.

FIGURE 1 is a plan view of the cell.

FIGURE 2 is a sectional view along A—A.

FIGURE 3 is a plan view of the cell.

FIGURE 4 is a sectional view along B—B.

FIGURE 5 is a plan view of the wiper assembly.

The names "Perspex" and "Permaplex" used in the following description are registered trademarks.

The cell shown in FIGURES 1 and 2 consists of a squat "Perspex" cylinder 20 which has a porous pot 22 mounted inside with its base a few cms. above the base of the cylinder 20. To the base of the cylinder 20 is cemented a bismuth disc 24, having approximately the same diameter as the porous pot 22, to act as the cathode of the cell. The electrolytically active area (43 cm.²) of the bismuth disc is defined by a strip of adhesive thermoplastic sheet 50 around the circumference of the bismuth disc. A "Perspex" stirrer 26 is suspended vertically through the centre of the porous pot 22 and coaxial within a glass tube 28 sealed in the bottom of the porous pot. The two soft sponge rubber wiper blades 30 are adhesively attached to the stirrer 26 which is arranged so that the wiper blades 30 are kept in contact with the surface of the bismuth cathode 24 to provide the wiping action. The pressure between the wiper blades 30 and the bismuth cathode 24 is just sufficient to cause partial deformation of the wiper blades 30.

The porous pot 22 is the anode compartment and contains three graphite blocks 32 as anodes. The space between the porous pot 22 and the cylinder 20 is the cathode compartment.

The cell is sealed by two rubber bungs 54 the outer of which also acts as a support for the porous pot.

Holes bored in the rubber bungs 54 accommodated an inert gas inlet 44, a thermometer 42, a catholyte inlet 46, a catholyte outlet 38, the catholyte 36, being forced out of the cell by the gas lift action of the blanketing inert gas, a chlorine outlet 40 to enable chlorine released at the anode 32 to be removed from the anode compartment, and a sampling tube 48 to enable samples of the catholyte to be removed for analysis.

The cell shown in FIGURES 3, 4 and 5 consists of a squat "Perspex" cylinder 60 cemented to a flat square "Perspex" base plate 62. The base plate 62 has a hole in the middle with a hollow "Perspex" funnel 64 cemented around the hole underneath the base plate 62. The lid of the cell is made from two concentric annular "Perspex" rings 66 and 68. The ring 66 covers the anode compartment 70 and the ring 68 covers the cathode compartment 72. The rings 66 and 68 are secured to each other and to the cylinder 60 by means of nylon screws 74 using silicone rubber rings 76 as gaskets.

The four carbon anodes 78, prepared by quartering a hollow graphite cylinder, are suspended from the anode lid 66 as shown.

The cathode 80 is a metal cylinder screwed onto a stainless steel shaft 82 driven by a motor (not shown). A "Perspex" cone 84 is cemented to the base of the cathode 80 to take up "dead space" and increase the current concentration. A mercury seal 86 is fitted to the steel shaft 82 where it passes through the cathode lid 68.

Four "Perspex" tubes let into the anode lid constitute chlorine outlets 88 and air inlets 90. Three further "Perspex" tubes let into the cathode lid constitute an argon inlet 92, an argon outlet 94 and a catholyte inlet 96.

The anode compartment 70 is separated from the cathode compartment 72 by a "Permaplex" C.20 cation exchange membrane 98 mounted on two "Perspex" rings 100 and 102 and secured by two neoprene O-rings 104 and 106 after being cemented to the rings 100 and 102 by a silicone rubber cement.

The top diaphragm ring 100 also carries the wiper supports 108 which are cemented to it and also slotted in the bottom ring 102. The wiper blades 110 are made of foamed latex rubber (Rubazote) and attached to the supports 108 by means of nylon screws 112 and "Perspex" strips 114. The wiper supports 108 are prevented from moving outwards by means of "Perspex" thrust block 116 screwed to the cylinder 60.

Example 1

Using an electrolytic cell as shown in FIGURES 1 and 2 and hereinabove described, the anode compartment was charged with ca. 50 mls. of saturated brine, and the cathode compartment with 120 mls. of a solution containing 248 gms. NaHSO₃, 31.5 gms. Na₂SO₃ and 200 gms. NaCl per litre. The wiping speed was 250 r.p.m.

The cell operated continuously. The metered flow through the cathode compartment was 8 ml./min. The total volume of catholyte in the circuit was 150 mls. The cathode compartment of the cell was blanketed with argon. The temperature of the cell was maintained at 20° C.

A measured electric current was passed through the cell and the current efficiency measured by analysing the cell effluent. Current efficiencies 100%, 89% and 91.5% were obtained with cathode current densities of 0.06, 0.08 and 0.12 amp. cm.⁻² respectively.

When the experiment was repeated under the same condition and using a current density of 0.12 amp. cm.⁻² but with the wiper blade raised (a) 0.124 mm. and (b) 0.625 mm. from the surface of the bismuth cathode the current efficiency fell to (a) 36.7% and (b) 29%.

The current yields in the above experiment have been corrected to allow for the known decomposition of dithionite at 20° C. At lower temperatures e.g. 5° C. the decomposition of dithionite is very small and hence these current efficiencies would be realised in practice.

Example 2

This was carried out under the same conditions and using the same apparatus as Example 1 but with the cathode compartment charged with 150 mls. of a solution containing 10 gm. acrylonitrile and 17 gm. NaCl per 150 mls. and using a current density of 0.04 amp. cm.⁻².

After one hour the catholyte was analysed by vapour phase chromatography which showed hexamethylene diamine to be present.

Example 3

This was carried out under the same conditions and in the same apparatus as Example 1 but with a titanium cathode, the anode compartment was charged with brine and the cathode compartment charged with a solution containing 248 gms. NaHSO₃, 31.5 gms. Na₂SO₃ and 200 gms. NaCl per litre.

The wiper was switched on. The cell operated continuously the catholyte flow being metered. The cathode compartment was blanketed with argon.

A measured electric current was passed through the cell and the current efficiency measured by analysing the cell effluent.

Example 12

Using the same apparatus as in Example 3, the anode compartment was charged with saturated sodium carbonate solution and the cathode compartment with an aqueous solution of sodium nitrate (34% w/w) and a trace amount of mercuric chloride.

The wiper was switched on and the cathode compartment blanketed with argon. The cell operated continuously, the catholyte flow being metered.

A measured electric current was passed through the cell and the current efficiency measured by analysis of the cell effluent.

The results obtained are given as run No. 1 in the Table. On switching the wiper off evolution of hydrogen was observed.

The results shown for run No. 2 were obtained by repeating run No. 1 but with no mercuric ions in the cathode compartment. Some hydrogen was evolved, the rate of evolution being independent of the wiper speed.

We claim:

1. A process for electrolysing a dissolved substance to give a dissolved product wherein the susceptibility of the process to diffusion limitation is decreased by subjecting at least one electrode, which electrode surface is poisoned, to a wiping action while immersed in the electrolyte, whereby the stagnant boundary layer adjacent the electrode is at least partially removed.
2. An electrolytic process according to claim 1 wherein there is present in the catholyte a surface poisoning agent.
3. An electrolytic process according to claim 1 wherein the poisoning agent is mercuric ions.

RESULTS
